Primary Examiner — Karen S Acker

(57) **CLAIM**

The ornamental design for a hose reel, as shown and described.

DESCRIPTION

Fig. 1.1 is a side view of the hose reel showing my new design.

Fig. 1.2 is another side view of thereof.

Fig. 1.3 is a front view thereof.

Fig. 1.4 is a top view thereof.

Fig. 1.5 is a perspective view thereof.

The broken lines in the drawings include portions of the hose reel that are not included in the claimed design.
